UNITED STATES PATENT OFFICE.

FRANK H. SKINNER, OF CHICAGO, ILLINOIS.

CROWN-PIN EXTRACTOR.

1,072,517.

Specification of Letters Patent. Patented Sept. 9, 1913.

Application filed September 2, 1908. Serial No. 451,304.

To all whom it may concern:

Be it known that I, FRANK H. SKINNER, a citizen of the United States, residing at Chicago, in the county of Cook and State 5 of Illinois, have invented certain new and useful Improvements in Crown-Pin Extractors, of which the following is a specification.

My invention relates to dental instruments 10 and has particular reference to devices for removing crown pins.

The object of the invention is to provide an improvement upon the vise-jaw type of 15 this class of tools, wherein the jaws are connected by a common base which has served to hold the jaws apart in a normally open position, to open the closed jaws when released and to support the screw for operating a post between the jaws.

20 In the present invention the above-mentioned base is relieved of the jaw-operating function, thus obviating the necessity of making the base out of metal adapted to withstand the bending strains imposed by 25 the opening and closing of the jaws, and allowing greater latitude in the selection of material. To this end I have, in my present invention, made the jaws and base in two pieces, the base forming an integral part 30 of one jaw while the other end is pivoted to the free end of the base. This construction not only relieves the base of the bending strains and liability to breakage therefrom, but also permits a larger relative movement 35 of the jaws.

With the above-named objects in view my invention consists in the novel construction, combination and arrangement of parts hereinafter described in detail, illustrated in the 40 drawing and incorporated in the appended claims.

In the drawing Figure 1 is a side elevation of a tool embodying my invention. Fig. 2 is edge elevation of same. Fig. 3 45 is a section taken on line X—X of Fig. 1. Fig. 4 is a perspective view of the post.

In the several views 2 represents one of the jaws of the tool having the integral curved base 3 in which is journaled a screw 50 4 provided with a thumb head 4'. This screw has threaded engagement with a hollow post 5 terminating in a pair of prongs 6 and 7, one for each side of the plane of movement of the jaws 2 and 3. At 8 the

companion jaw 9 is pivoted to the free end 55 of the base 3, which permits the jaws to move relatively to each other to the desired extent without imposing any strain upon the base 3.

In Fig. 1 a crown pin 10 is shown in dotted lines in a dotted tooth 11. The jaws are, as shown, clamped upon the pin 11 by means of a clamping screw 12 which passes through an opening in the jaw 9 and has threaded engagement with a threaded bore in the 60 jaw 2. By relieving the base of the spring function it may be made as thick and strong as desired, or, in other words, its construction need not be limited to any elastic quality and proportion. The head of the screw 65 4 supports the latter on one side of the base against longitudinal movement in one direction, and against movement in the opposite direction the screw is held by a collar 70 13 secured thereto on the opposite side of the base as shown. The clamp screw 12 supports the post 5 laterally in a plane at right angles to the plane of movement of the jaws 2 and 9 by its engagement of a slot 14 in the post shown in Fig. 4. Between said slot 75 and the tips or prongs 6 and 7 is a bridge 15 which supports the prongs against spreading apart. The jaws, being set apart by the wide base 3, are capable of taking a very firm pinch hold upon a dowel or crown 80 pin with the extreme tips of their beaks curved toward each other. The screw 4, being journaled in the base 3 and telescoping the post, also materially assists in supporting the post in proper alignment with the 85 jaws of the tool.

I claim as my invention—

In combination with the jaws, of a base common to both said jaws, said base being an integral portion of one of said jaws and 90 having a pivotal connection with the other jaw, a screw for moving said jaws, a post having a part engaging said screw and having another part adapted to rest upon the root of a tooth, and a post-actuating screw 95 mounted in said base between said jaws.

In testimony whereof I have hereunto set my hand in the presence of two subscribing witnesses.

FRANK H. SKINNER.
